CLAIM

The ornamental design for cargo restraining enclosure, as shown and described.

DESCRIPTION

FIG. 1 is a bottom perspective view of a cargo restraining enclosure showing our new design;

FIG. 2 is a top perspective view thereof;

FIG. 3 is a bottom plan view thereof;

FIG. 4 is a top plan view thereof;

FIG. 5 is a front view thereof;

FIG. 6 is a rear view thereof;

FIG. 7 is a right side view thereof;

FIG. 8 is a left side view thereof;

FIG. 9 is a top perspective view shown with the enclosure shown in a partially opened position;

FIG. 10 is a top perspective view with the enclosure shown in a fully opened position;

FIG. 11 is a front view of FIG. 10;

FIG. 12 is a rear view of FIG. 10;

FIG. 13 is a right side view of FIG. 10; and,

FIG. 14 is a left side view of FIG. 10.
